UNITED STATES PATENT OFFICE.

JOHN G. SMART, OF WINNIPEG, MANITOBA, CANADA.

LOOSE-LEAF BINDER.

Application filed November 6, 1924. Serial No. 748,162.

The invention relates to improvements in loose leaf binders and an object of the invention is to provide means which will permit of the adjusting towards and away from each other of the posts utilized for holding the leaves, thereby permitting one to adjust the posts as occasion requires to accommodate the perforations of the leaves used.

A further object is to provide a construction which can be readily adapted to the various types of existing loose leaf binders now in use.

A further object is to construct the appliance in a simple, inexpensive and durable manner and so that the adjustment can be quickly and effectively made and such that the appliance will not interfere in any way with the ready and quick removal or insertion of leaves.

20 A further object is to construct the device so that one can lock the slides or blocks of the top plate to the top plate when desired.

A further object is to provide adjustable stops to prevent edge shifting of the leaves.

25 With the above and other minor objects, which will become more apparent as the description proceeds, in view the invention consists essentially in the arrangement and construction of parts hereinafter more particularly described, reference being had to the accompanying drawing in which:

Fig. 1 is a perspective view of a binder embodying my invention.

Fig. 2 is an enlarged detailed vertical sectional view through a portion of the binder, the section being longitudinally and centrally through the slots in the plates.

Fig. 3 is a vertical cross sectional view at 3—3' Figure 2.

40 Fig. 4 is a perspective view showing the type of collar used on the adjusting screws.

Fig. 5 is an enlarged detailed vertical sectional view at 5—5' Figure 2.

Fig. 6 is a perspective view of one of the adjusting slides or blocks.

45 In the drawing like characters of reference indicate corresponding parts in the several figures.

In loose leaf systems it is common practice to bind the loose leaves 1 between upper 50 and lower binding plates 2 and 3, the leaves being provided with perforations 4 which receive binding posts 5 and 6 extending between the plates. Binding posts are now made so that they can be screwed together 55 as best shown in Figures 2 and 3, in order

to permit one to increase the thickness of the binder, but so far as I am aware no provision has as yet been made to permit of the adjustment towards or away from each other in order to accommodate the perforations of the sheets which it may be desired to bind in the binder.

I have herein shown my invention as applied to one of the simpler and less expensive types of binders, but in this connection I wish it to be distinctly understood that the invention can be applied with slight modifications to the various types of binders now used.

The front and back covers 7 and 8 of the binder are hinged in the usual manner as indicated at 9 to the top and bottom plates and the top and bottom plates are both provided with lengthwise extending centrally 75 positioned end slots 10 and 11, these slots having their outer ends open and the side walls 12 and 13 thereof converging upwardly.

In each of the slots of the lower plate I 80 mount a slide or block 14 adapted to slide therein and having tapering sides complementary to the walls 12 and 13. These blocks carry the posts 5 and 6, the lower ends of which are screwed into the blocks 85 and obviously when the blocks 14 are moved endwise within the slots, the posts will be shifted towards or away from each other, depending on the movement given. The upper ends of the posts extend centrally 90 through the slots 10 and 11 and are received within similar upper slides or blocks 15 and 16 which are provided with means for clamping the blocks to the posts. The upper slides or blocks are slidably mounted in the upper slots for endwise movement, in the same manner as the lower ones and they are provided each with an opening 17 for the post and a lengthwise extending slot 18 extending from one end of the block inwardly to the opening 17.

An adjusting screw 19 is carried by each of the blocks 15 and 16, the adjusting screw having one end thereof rotatably mounted in the leg 20 of the block and the other end thereof screw threaded through the leg 21 of the block.

A finger grip 22 is permanently secured to the non-threaded end of the screw, the finger grip being formed integrally with a shoulder 23 which engages the outer face of the block and prevents end movement of

the screw in one direction. A collar 24 is placed on each screw within the slot 18, this collar being adapted to prevent end movement of the screw in the opposite direction to that just intimated.

In the present instance I have shown the screw as provided with a circumscribing channel 25 and the collar is initially of a U-shape and is primarily passed into the channel and then the open ends of the collar are pressed together around the screw. The collar and the shoulder prevent end shifting of the screw in respect to the leg 20, but allow the same to rotate freely therein.

According to the above arrangement, it will be apparent that by turning the screw in one direction, one can spread the legs of the block and in so doing will initially release the block from the entered post and if the screwing in the same direction be continued he will subsequently lock the block to the top plate as the spreading of the legs will cause the lower part of the block to frictionally jam in the slot. The reverse movement of the screw will obviously tighten the blocks on the posts.

The open ends of the slots are closed by pairs of jam plates 26 and 27, the plates being connected by a fastening screw 28. The ends of the top and bottom plates are partially cut away so as to keep the outer faces of the plates 26 and 27 flush with the top and bottom faces of the plates 2 and 3.

One can adjust the plates 26 and 27 in or out with respect to the slots, depending on the width of leaf used in the binder.

When one initially desires to place some perforated leaves in my binder, he releases the screws 22 and removes the top plate from the posts. He then moves the posts 5 and 6 towards or away from each other to position them so that they will receive the perforations of the sheets or leaves it is desired to enter in the binder. The posts having been properly positioned or centred, one then places the leaves on the posts in the usual manner and subsequently replaces the top plate, the slides or blocks 15 and 16 being adjusted in the top slots in order to permit the posts to enter the opening 17 therein. This being accomplished, one then tightens up the screws to cause the top blocks to tightly grip the posts. Prior to tightening the screws, one can press down on the top plate so that when the screws are finally tightened up, the leaves will be firmly bound. Any edge shifting of the leaves in respect to the binder is prevented by the jam plates 26 and 27 which are adjusted to engage the upper and lower edges of the inserted leaves.

If one desires to add further leaves to the binder, he will turn the screws 22 far enough to release the posts and jam the top blocks in the slots. He then would re-

move the top plate and the blocks 15 and 16 would not shift. This locking of the top blocks in the slots obviously avoids having to adjust these blocks each time new leaves are to be put in the binder.

Whilst I have entered into a detailed description of the particular means utilized for clamping the top slides to the posts and locking them to the plate, still I wish it to be distinctly understood that I do not desire to be limited to the particular means shown as this could be readily modified to accommodate it to the various types of binders now on the market and without departing from the spirit of the appended claims.

What I claim as my invention is:

1. In a loose leaf binder, the combination with top and bottom binding plates, of members freely sliding in the plates and movable towards or away from one another and binding posts carried by the members of the bottom plate and passing through the members of the top plate, means for releasably fastening the top members to the posts and means for locking the members in the plates.

2. In a loose leaf binder, the combination with top and bottom binding plates adapted to receive perforated leaves therebetween, of posts slidably carried by the bottom plate to permit of the adjustment of the posts to accommodate the distance between centres of the leaf perforations, said posts passing through the top plate, sliding members carried by the top plate and receiving the upper ends of the posts, means for releasably clamping the said sliding members to the posts and adjustable means carried by the top and bottom plates and arranged to contact with the edges of the upper and lower leaves.

3. In a loose leaf binder, the combination with top and bottom binding plates adapted to receive perforated leaves therebetween, of blocks carried by the bottom plate and endwise slidably in respect to the plate, upstanding binding posts carried by the blocks and passing through the perforations of the leaves and through lengthwise extending slots provided in the upper binding plate, upper blocks slidably mounted in the slots of the upper plate and having openings therein to receive the posts and slots extending from said latter openings to one end of the block and adjusting screws carried by the latter blocks and crossing the slots, said screws being designed to jam the blocks to the posts when turned in one direction and to spread the blocks to prevent sliding thereof in the slots of the top binding plate upon the screws being turned in the opposite direction.

4. In a loose leaf binder, the combination with top and bottom binding plates, provided with lengthwise extending slots and adapted to receive therebetween a plurality

of perforated leaves of lower blocks slidably mounted in the slots of the bottom plate, binding posts carried by the lower blocks and extending upwardly through the leaves and through perforations of the slots of the upper plate, split blocks slidably mounted in the slots of the upper plate and receiving the upper ends of the posts, adjustable jam screws carried by the upper blocks and designed when turned in one direction to jam the blocks on the posts and when turned in the opposite direction to spread the said latter blocks in the channels.

5. In a loose leaf binder, the combination with top and bottom binding plates, provided with lengthwise extending slots and adapted to receive therebetween a plurality of perforated leaves, of lower blocks slidably

mounted in the slots of the bottom plate, binding posts carried by the lower blocks and 20 extending upwardly through the leaves and through perforations of the slots of the upper plate, split blocks slidably mounted in the slots of the upper plate and receiving the upper ends of the posts, adjustable jam 25 screws carried by the upper blocks and designed when turned in one direction to jam the blocks on the posts and when turned in the opposite direction to spread the said latter blocks in the channels and adjustable jam plate located in the outer ends of the slots and arranged to contact with the upper and lower edges of the inserted leaves.

Signed at Winnipeg, this 12 day of September 1924.

JOHN G. SMART.
